Primary Examiner — Cynthia R Underwood*(74) Attorney, Agent, or Firm* — Jason H. Vick; Sheridan Ross, PC(57) **CLAIM**

The ornamental design for a cord holding device, as shown and described.

DESCRIPTION

FIG. 1 is a top perspective view of a cord holding device of the claimed design;

FIG. 2 is a bottom perspective view of the cord holding device of FIG. 1;

FIG. 3 is a top plan view of the cord holding device of FIG. 1;

FIG. 4 is a bottom plan view of the cord holding device of FIG. 1;

FIG. 5 is a right elevation view of the cord holding device of FIG. 1;

FIG. 6 is a left elevation view of the cord holding device of FIG. 1;

FIG. 7 is a front elevation view of the cord holding device of FIG. 1; and,

FIG. 8 is a rear elevation view of the cord holding device of FIG. 1.

1 Claim, 5 Drawing Sheets(56)
